UNITED STATES PATENT OFFICE

2,147,766

FLUID-OPERATED PUMP PISTON DEVICE

Clarence J. Coberly, Los Angeles, Calif., assignor
to Roko Corporation, Reno, Nev., a corporation
of Nevada

Original application April 21, 1937, Serial No.
138,176. Divided and this application January
26, 1938, Serial No. 187,917

5 Claims. (Cl. 103—46)

The subject matter of this application is shown but not claimed in my Patent No. 2,081,223, issued May 25, 1937, for "Fluid operated deep well pump", and this application is a division of my copending application Serial No. 138,176, filed April 21, 1937, for "Valve for fluid-operated pump mechanism".

Objects and features of the invention will be made clear in the following specification taken 10 in connection with the drawing, in which:

Fig. 1 is a vertically sectioned view showing the upper end of a fluid operated pump embodying the features of my invention.

Fig. 2 is a vertically sectioned view complementary to Fig. 1, showing the central section of the pump embodying the features of my invention.

Fig. 3 is a vertically sectioned view complementary to Fig. 2, showing the lower end section of the pump.

Referring to the drawing, I show a fluid operated pump 10 of the general character shown in my copending application Serial No. 138,176, to which reference is made for specific details of construction and method of operation of the pump. The upper end of the pump 10 is secured to the lower end of a fluid delivery pipe 11 by which operating fluid under relatively high pressure is delivered to a motor cylinder 12 having a motor piston 13 slidably disposed therein, and 20 the pump 10 also has a pump cylinder 14 having a pump piston 15 disposed therein. Connected to and projecting upwardly from the power piston 13 is a pilot rod 16, and a piston rod 17 is provided to connect the power piston and the motor piston 15, and secured to the lower end of the motor piston is a rod 18. It will be noted that the pilot rod 16, the power piston 13, the piston rod 17, the pump piston 15, and the rod 18 are equipped with axial passages 19, 20, 21, 22, and 23, respectively through which high pressure fluid may pass from the fluid delivery pipe 11 to a tubular member 24, where it acts upwardly against the lower end of the rod 18 to balance the downward pressure on the upper end of the pilot rod 16.

The pilot rod 16, the piston rod 17, and the rod 18 are connected to the pistons 13 and 15, in the manner shown, by use of external threads 25 on the rods which engage threads 26 formed near the inner ends of counterbores 27 in the pistons, the rods having conical ends 28 at the extreme ends thereof which engage conical seats 29 at the inner extremities of the counterbores 27 so that a positive fluid seal is thereby formed between the ends of the rods and the pistons which

they engage. A feature of the invention is to provide a means for connecting the rods to the pistons so that they will be practically concentric, but at the same time the rods are provided with sufficient flexibility of connection with the 5 pistons to compensate for small deviations from perfect axial alignment of cooperating parts. To accomplish this result, each of the counterbores 27 has an intermediate bore portion 30 formed adjacent the outer ends of the threads 25 which 10 is ground to fit snugly that portion 31 of the rod adjacent the threads 25, thereby producing an axial alignment of the end of the rod which is independent of the threads 25 and 26. Each of the counterbores 27 has an outer bore portion 33 15 which is ground to a diameter slightly larger than the rod so that the portion 31 of the rod within the outer end of the counterbore 27 may flex laterally should the rod be slightly out of alignment with other parts of the pump structure 20 with which it cooperates. For this purpose, the outer bore portion 33 may be ground to a diameter approximately 0.002 inch greater than the diameter of the portion 31 of the rod. By the use of a construction as hereinabove described, the 25 end of each rod 16, 17, and 18 is given a spaced two-point centralizing engagement with the piston to which it is attached. For instance, the conical end 28 of each rod engages a conical seat 29 at the inner end of a counterbore 27, and a portion 31 of the rod spaced from the end thereof engages an intermediate portion 30 of the counterbore 27. Beyond the intermediate portion 30, the 30 rod may flex within the outer end portion 33 of the counterbore 27 should minute disalignment 35 of cooperating parts require the same.

I claim as my invention:

1. A piston and rod structure of the character described, comprising: a piston having a counterbore with a seat at the inner end thereof and a 40 threaded portion adjacent said seat; and a rod adapted to enter said counterbore, said rod having a seat engaging portion at its extremity, threads adjacent its extremity for engaging the threads of said counterbore, and a cylindrical wall portion 45 adjacent said threads of said rod for engaging the wall of said counterbore near the outer ends of said threads of said counterbore.

2. A piston and rod structure of the character described, comprising: a piston having a counterbore with a seat at the inner end thereof and a threaded portion adjacent said seat; and a rod 50 adapted to enter said counterbore, said rod having a seat engaging portion at its extremity, threads adjacent its extremity for engaging the

threads of said counterbore, and a cylindrical wall portion adjacent said threads of said rod for engaging the wall of said counterbore intermediate the ends thereof, there being a clearance between the outer ends of said counterbore and said rod.

3. In a deep well pump, the combination of: a cylinder; a piston in said cylinder, said piston having a fluid passage therein adapted to convey fluid through said piston; a piston rod having a fluid conduit therein adapted to communicate with said fluid passage to convey fluid therethrough to or from said fluid passage; and means connecting said piston rod to said piston so as to form a fluid-tight joint therebetween, said means permitting lateral play of said piston rod relative to said piston.

4. A piston and rod structure of the character described, including: a first piston having a fluid passage therethrough adapted to convey fluid through said piston; a second piston having a fluid passage therethrough adapted to convey fluid through said second piston; a piston rod having a fluid conduit therein adapted to communicate with said passages to provide fluid com-

munication between said passages; and means for connecting said piston rod to said pistons so as to form fluid-tight joints between said rod and said pistons, said means permitting lateral play of said rod relative to said pistons.

5. A piston and rod structure of the character described, including: a first piston having a fluid passage therethrough adapted to convey fluid through said first piston; a second piston having a fluid passage therethrough adapted to convey fluid through said second piston; a first rod adapted to be connected to said first piston; a second rod for connecting said pistons; a third rod adapted to be connected to said second piston, said rods having fluid conduits therein adapted to communicate with said passages so that fluid may pass in sequence through said first rod, said first piston, said second rod, said second piston, and said third rod; and means for connecting said rods to said pistons so as to form fluid-tight joints between said rods and said pistons, said means permitting lateral play of said rods relative to said pistons.

CLARENCE J. COBERLY. 25
